UNITED STATES PATENT OFFICE.

HENRY H. FRICK, OF FRICKS, PENNSYLVANIA.

COLLAPSIBLE CENTERING.

1,178,712.

Specification of Letters Patent. Patented Apr. 11, 1916.

Application filed August 6, 1915. Serial No. 44,090.

To all whom it may concern:

Be it known that I, HENRY H. FRICK, a citizen of the United States, residing at Fricks, in the county of Bucks and State of Pennsylvania, have invented a new and useful Collapsible Centering, of which the following is a specification.

The device forming the subject matter of this application is adapted to be employed 10 for supporting a collapsible form of the sort commonly used in connection with concrete operations.

The invention aims to provide novel means whereby a collapsing of such a form 15 may be brought about readily, and to provide novel means whereby the form may be maintained in a distended condition.

It is within the province of the disclosure to improve generally and to enhance the 20 utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made within 30 the scope of what is claimed, without departing from the spirit of the invention.

In the accompanying drawings:—Figure 1 shows in side elevation, a portion of a supporting arch for a concrete mold, in which the present invention has been embodied; Fig. 2 is a horizontal section of the structure shown in Fig. 1; Fig. 3 is a perspective showing one of the skewbacks; Fig. 4 is a perspective showing one of the voussoirs; Fig. 5 is a perspective showing one of the heads which constitutes a part of the tie; Fig. 6 is a perspective showing the operating shaft; Fig. 7 is a perspective delineating another head of the tie; Fig. 8 is an end elevation showing a modified form of the invention; Fig. 9 is an elevation showing one of the elements employed in that form of the invention which is disclosed in Fig. 8; Fig. 10 is an elevation showing the connection 45 employed in that form of the invention appearing in Fig. 8; Fig. 11 is an elevation showing one end of the standard as employed in Fig. 8; Fig. 12 is an end elevation showing a modified form of the invention, the structure in Fig. 12 being viewed from 50 an opposite end, as compared with Fig. 8.

In the accompanying drawings and referring particularly to Figs. 1 to 7 both inclusive, there is shown a pair of skewbacks 1 and 2 each comprising a base 3 and a 60 socket 4 having circular openings 5. It is contemplated that the invention as disclosed in Figs. 1 to 7 shall be used in connection with a supporting arch of that sort which is shown in my prior Patent No. 1,019,314, to 65 which reference may profitably be had. The arch comprises terminal voussoirs 6 of such a cross section as to fit closely but slidably in the socket 4, the voussoirs 6 comprising an angularly disposed arm 7 provided with 70 openings 8. In the voussoir 6 intermediate its ends is formed an opening 12.

The invention comprises a voussoir 9 of the sort shown in my prior patent above alluded to, the same comprising arms 10 between which the arm 7 of the terminal voussoir 6 extends. A pivot element 11 unites the voussoirs 9 and 6, the pivot element being mounted in the opening 12 and in openings in the ends of the arms 10 of the voussoir 9. In the arms 10 there are formed openings 14. In any pair of the openings 14 and in one of the openings 8 may be mounted a securing element 15 which prevents relative movement between the voussoirs 6 and 9 on the pivot pin 11. In the terminal voussoir 6 is fashioned an elongated slot 16 having an enlargement 17 of circular contour and of the same size as the openings 5 in the socket 4.

The invention comprises a pair of shafts 18, one of which is shown in detail in Fig. 6. The shaft 18 comprises a flattened stem 19, the edges of which are rounded as shown at 20 to conform to the curvature of the openings 5 and 17, the stem 19 of the shaft being of such a thickness that it may be slidably received in the slot 16 of the voussoir 6. At one end, the shaft 18 is equipped with an enlarged head 21 having notches 22, so that the head constitutes a ratchet wheel adapted to be engaged by a pawl 24 pivoted at 25 to each skewback 1—2. The head 21 terminates in a boss 23 suitably shaped to receive a wrench or other rotating tool (not shown).

From the foregoing description it will be obvious that when the flattened stem 19 of the shaft 18 is located in the opening 17 of the voussoir 6 and in the openings 5 of the skewback, and stands crosswise of the slot 16, the voussoirs 6 cannot move downwardly, and consequently, the arch of which the

voussoirs constitute parts will be supported. A wrench may be applied to the squared boss 23 to secure a rotation of the shaft 18, whereupon the flattened stem 19 of the shaft 5 18 will be so disposed that its longer dimension will stand vertically. Under such circumstances, the flattened stem 19 is received in the slot 16 of the terminal voussoir 6, and then the arch will be collapsed as the terminal 10 voussoirs 6 move downwardly. When the flattened stem 19 of the shaft 18 stands crosswise of the slot 16 and is located in the opening 17, an accidental rotation of the shaft and a consequent collapsing of the 15 arch may be avoided by engaging the pivoted pawl 24 in any of the notches 22 of the ratchet head 21.

In connection with each pair of voussoirs 1-2 there is employed a tie, which is a composite structure. The tie embodies a head 26, shown in Fig. 7, the head having a longitudinal slot 27 and a terminal, circular opening 28 of approximately the same size as the openings 5 and 17 in the skewback and 25 in the terminal voussoir respectively. The head 26 terminates at one end in a tubular socket 29 carrying a set screw 30. The socket 29 is adapted to receive one end of an intermediate section 31 of the tie, the section 30 31 being in the form of a rod or bar, the end of which is adapted to be held adjustably by the set screw 30. The other end of the section 31 of the tie is flattened and is received between bifurcations 32 of a head 33 shown 35 in Fig. 5, the extremity of the intermediate section 31 being held to the bifurcations 32 by means of a pivot element 34. The head 33 is equipped with a longitudinal slot 35. The effective length of the tie is regulated 40 by loosening the set screw 30 and adjusting one end of the intermediate section 31 in the socket 29.

In practical operation, the flattened stem 19 of the shaft 18 in the skewback 2 is received in the slot 35 formed in the head 33 of the tie. The flattened stem 19 of the shaft 18 on the skewback 1 is rotatably received in the opening 28 of the head 26 of the tie. When the shaft 18 of the skewback 50 2 is rotated, the head 23 will act as a crank arm and will increase or diminish the effective length of the tie.

If it is desired to rotate both of the shafts 18 to effect a collapsing of the arch then the 55 tie must be slid off the flattened stems 19 of both shafts 18. If it is desired to collapse the arch by rotating that shaft 18 which is mounted in the skewback 1, such an operation may be brought about, since the flattened stem 19 of the shaft 18 in the skewback 1 is journaled in the opening 28 of the head 26 of the tie.

It is possible to lodge the flattened stem 19 of the shaft 18 in the skewback 1, in the 60 slot 27 of the head 26 of the tie. Under such

circumstances, both shafts will be prevented from rotating, the flattened shanks or stems 19 of the shafts standing crosswise of the slots 16 of the voussoirs 6, and being located in the enlargements 17 of the said slots. 70 Therefore, at times, and at the will of an operator, the tie may be used for preventing a rotation of the shafts 18 and a consequent collapsing of the arch.

In Figs. 8, 9, 10 and 11, there is shown a 75 modified form of the invention, in which there appears a circular, metallic casing 36, the longitudinal edges of which are overlapped and slidably connected as shown at 37. Assembled with the casing 36 is a standard 80 38 which corresponds to the skewback 2, the standard embodying a socket 39, corresponding to the socket 4, the socket having an opening 50, represented in Fig. 3 by the opening 5. A support 40 is assembled with 85 the casing 36, the support taking the place of the voussoir 6 of Fig. 4. In the support 40 there is formed an elongated slot 41 having an enlargement 42. The invention comprises a connection 48 having a slot 49 90 adapted to receive the flattened end of a shaft 46 journaled in the openings 50 and coacting with the slot 41 and its enlargement 42 as hereinbefore described, the connection 48 corresponding in function to the head 33. The shaft 46 is held against rotation by 95 means of a pawl 47 pivoted to the socket 39 of the standard 38. Links 43 are pivoted at their outer ends as shown at 44 to the casing 36 and are pivoted at their inner ends, 100 as shown at 45 to the extremities of the connection 48. The operation of the structure above described, need not be gone into in detail, in view of what has been stated hereinbefore in connection with that form of the 105 invention appearing in Fig. 1. It will be understood, however, that when the shaft 46 is rotated, the support 40 will be permitted to telescope into the socket 39, the connection 48 being tilted on the head 33, to draw 110 the links 43 inwardly.

In Fig. 12 of the drawings a casing 51 appears, the same having its longitudinal edges overlapped and slidably connected as 115 shown at 52. The standard is shown at 53 and is provided with a socket 54 receiving one end of the support 55, the same having a slot 56 corresponding to the slot 41. The connection appears at 57 and is provided with an elongated slot adapted 120 to receive the flattened portion 58 of the shaft, a plurality of links 59 being pivoted to the casing 51 and to the connection 57, Fig. 12 being introduced to show that the 125 number of links may be increased or diminished as the exigencies of the proposed use may demand, four links being employed in Fig. 12, and two links in Fig. 8.

Reverting to that form of the invention which is shown in Fig. 1, it will be under- 130

stood that as many skewbacks 1—2 and corresponding parts as may be desired, may be mounted on the flattened stems 19 of the shafts 18, the shafts being of any desired 5 length.

If the shaft 18 is mounted in the circular opening 28 of the member 26, the arch may be collapsed without changing the space between the skewbacks.

Having thus described the invention, what is claimed is:

1. In a concrete mold, a socket; a mold supporting element slideable in the socket and provided with a longitudinal slot 15 having an enlargement; and a shaft journaled in the socket, the shaft including a flattened stem rotatable in the enlargement to stand crosswise of the slot, thereby to uphold the mold supporting element, and rotatable in the enlargement to be received in the slot, thereby to permit a telescoping of the mold supporting element into the socket.

2. In a concrete mold, a socket; a mold 25 supporting element slideable in the socket and provided with a longitudinal slot having an enlargement; a shaft journaled in the socket, the shaft including a flattened stem rotatable in the enlargement to stand crosswise of the slot, thereby to uphold the mold supporting element, and rotatable in the enlargement to be received in the slot, thereby to permit a telescoping of the mold supporting element into the socket; and 30 releasable means for holding the shaft against rotation.

3. In a concrete mold, a socket; a supporting element slideable in the socket and provided with an elongated slot having an 40 enlargement; a shaft journaled in the socket and having a flattened stem rotatable in the enlargement to stand crosswise of the slot thereby to uphold the supporting element, and rotatable in the enlargement to

be received in the slot thereby to permit 45 a telescoping of the supporting element into the socket; a form assembled with the supporting element; a crank arm on the flattened stem; and a link affording an operative connection between the form and the 50 crank arm.

4. In a concrete mold, a pair of skewbacks embodying sockets; an arch including voussoirs slideable in the sockets, the voussoirs being equipped with elongated slots 55 having enlargements; shafts journaled in the voussoirs and provided with flattened stems rotatable in the enlargements to stand crosswise of the slots, thereby to support the voussoirs, and rotatable in the enlargements to be received in the slots; and a tie 60 having openings receiving the flattened stems of the shafts to prevent a rotation of the stems.

5. In a concrete mold, a pair of skewbacks, each including a socket; an arch comprising voussoirs slideably received in the sockets, the voussoirs having elongated slots provided with enlargements; shafts journaled in the skewbacks and comprising 70 flattened stems rotatable in the enlargements to stand crosswise of the slots and rotatable in the enlargements to be received in the slots; and a tie comprising pivotally connected parts, one of which is provided with an opening in which the stem of one shaft is rotatable, the other of which is provided with an opening receiving the stem of the other shaft to connect said part for 75 movement with said other shaft.

In testimony that I claim the foregoing as my own, I have hereto affixed my signature in the presence of two witnesses.

HENRY H. FRICK.
